UNITED STATES PATENT OFFICE.

GUSTAF EMIL HESSE, OF BROOKLYN, NEW YORK, ASSIGNOR OF TWO-
THIRDS TO GEORGE H. ROBINSON, OF NEW YORK, N. Y.

ACETYLENE-GAS LAMP.

SPECIFICATION forming part of Letters Patent No. 606,385, dated June 28, 1898.

Application filed November 2, 1897. Serial No. 657,144. (No model.)

To all whom it may concern:

Be it known that I, GUSTAF EMIL HESSE, a resident of the city of Brooklyn, in the county of Kings and State of New York, have 5 invented a new and useful Improvement in Acetylene-Lamps, of which the following is a specification.

This invention, though applicable to stationary lamps, is more especially intended for 10 lamps which are portable.

A lamp embodying my invention comprises a receptacle for carbid, which constitutes the generator, and a reservoir for water above said receptacle.

15 The principal object of the invention is to obtain an even and controllable supply of water to the carbid, and for this purpose I employ between the water-reservoir and the carbid-receptacle below it one or more wicks, 20 through which the water is supplied from said reservoir to said receptacle by gravitation in a constant, but restricted, flow instead of intermittently, as when it is supplied in drops, the result of such constant flow being a steady 25 flame instead of a flickering one.

Figures 1 and 2 represent vertical sections taken at right angles to each other, of a lamp embodying my invention, the section Fig. 2 being taken in the line 2 2 of Fig. 1. Fig. 3 30 represents a vertical section taken in the line 3 3 of Fig. 2.

Similar letters of reference designate corresponding parts in all the figures.

A designates the receptacle for the carbid, 35 which constitutes both the base of the lamp and the generator and is represented as enveloped by a jacket A', containing some material which is a poor conductor of heat.

B is the water-reservoir, consisting of a 40 closed vessel, the lower part of which is screwed into a socket in the head of the carbid-receptacle A and forms a removable cover thereto. This reservoir B is represented as surrounded by a jacket B', containing 45 some material which is a poor conductor of heat.

C designates the burner, which will be hereinafter spoken of as the "main" burner, between which and the carbid-receptacle there is 50 a pipe D, which passes water-tight through the bottom of the water-reservoir B and is open

to the upper part of the carbid-receptacle. The burner and the upper part of the pipe D are represented as supported by a pillar E, which I prefer to make of some poor heat-conducting material—porcelain, for example. 55

F is a wick-tube represented (see Fig. 2) as having two branches, both branching from a cock G within the water-reservoir and extending downward through the bottom of said reservoir into the upper part of the carbid-receptacle. At the bottom of this cock, between the wick-tubes, there is a nozzle or short tube a, which reaches nearly to the bottom of the water-reservoir B. The cock G is represented as what is known as a "three-way" cock, which may be brought to a position to open both wick-tubes to the short tube a, as shown in Fig. 2, to allow water to flow from the reservoir B through said tube a, the cock 60 G, and the two wicks I, the upper parts of which are contained in the tubes F and the lower parts of which hang below the said tubes into the carbid-receptacle, the only communication between the water-reservoir and the carbid-receptacle being through these 65 wicks, which so restrict the natural downward flow of the water by gravitation as to enable its supply to be better regulated by the cock 70 G than it could be without the wicks. 75

Between the pipe D, which may be termed the "gas-conduit," and the burner C there is a cock J for the purpose of shutting off the gas from the burner. This cock J has such a connection with the cock G that when the 80 said cock J is open to the main burner C to supply the latter with gas for illumination, as shown in Figs. 1 and 2, the cock G is also open to the tube a and wick-tubes F, as shown in Fig. 2, so that the water is then supplied 85 to the carbid in the receptacle A for the generation of the gas, which then flows through the pipe D to the burner. The same connection between the two cocks causes the cock G to shut off the supply of water to the wicks and 90 the carbid-receptacle when the cock J is turned to a position to shut off the gas from the pipe D to the main burner C. The connection between the two cocks may be made 95 by any means by which the two are made to operate as above described. It is represented as consisting of an eccentric b on the plug of 100

the cock J and a rod c, connecting said eccentric with a short lever d on the plug of the cock G, the said lever d being within the water-reservoir, and the said rod c passing freely 5 through a small hole in the top of the said reservoir, the said hole serving also as a vent for the admission of air to said reservoir.

In order to provide, after the gas is shut off from the main burner C and the water is 10 shut off from the carbid-receptacle, for the combustion of the gas which continues for some time to be slowly generated in the receptacle A, owing to the moisture remaining in the carbid, I provide in the plug-seat of 15 the burner-cock J on one side of the plug of said cock a small cavity e, Fig. 1, from which there are small holes or passages f, (see Figs. 1 and 3,) leading from the upper part of the said cavity through the shell of the said cock 20 to a point near the main burner C, and I construct the said cock as a three-way-cock, as shown in Fig. 1, so that when the gas is shut off from the main burner C it may be turned onto the cavity e and may issue in a jet or 25 jets through the passages f, at the outer orifices of which it may be burned. Thus the burner-cock is not only made to perform the function of a safety-valve, but the passages f constitute a supplementary burner for the 30 burning of the gas which escapes through it while it is performing that function, and the offensive odor which results from letting it escape through an ordinary safety-valve is thus got rid of.

35 I have represented as provided around the passages f a cap h, which will serve to prevent the accidental blowing out of the flames of the small jets issuing from the said pas-

sages, the said cap having holes i around its lower part for the admission of air to said jets and openings j at the top for the escape of the gases of the combustion taking place from said jets. This cap is, however, not absolutely essential to the carrying out of my invention. I have also represented in the 45 shell of the burner-cock a by-pass g, which is constantly kept open, so that there may be a small flame supplied by it for igniting the jets from f f when the passage to the main burner is closed.

What I claim as my invention is—

1. The combination with the carbid-receptacle and the water-reservoir above it, of a wick-tube having a plurality of branches between said receptacle and reservoir and a 55 cock in said wick-tube for controlling all its branches, substantially as herein described.

2. In an acetylene-lamp, the combination of a carbid-receptacle constituting a generator, a water-reservoir, a water-cock between 60 said reservoir and said generator, a main burner and a supplementary burner supplied from said generator, a gas-cock common to both of said burners for opening either when the other is closed, and a connection between 65 the said cocks for opening and closing the water-cock and the main burner simultaneously and for closing or opening the supplementary burner while the main burner and the water-cock are respectively open or closed, 70 substantially as herein described.

GUSTAF EMIL HESSE.
